UNITED STATES PATENT OFFICE.

EUGENE KRAFT, OF SPOKANE, WASHINGTON.

VAPORIZER.

Application filed January 22, 1924. Serial No. 687,718.

To all whom it may concern:

Be it known that I, EUGENE KRAFT, a citizen of the United States, residing at Spokane, in the county of Spokane and 5 State of Washington, have invented new and useful Improvements in Vaporizers, of which the following is a specification.

The object of this invention is to provide means for more completely vaporizing the 10 explosive mixture in the combustion chamber of an explosion engine and also vaporizing any lubricating oil that may be pumped into the chamber by defective action of the engine pistons.

15 A further object is to provide means for vaporizing the explosive mixture prior to the first explosion to facilitate starting of the engine.

20 A further object is to attach the structure of this invention to the usual skeleton gasket which is interposed between the block and head of the engine so that the application of the device of this invention may be made to any engine without altering or drilling 25 either the head or block.

Other features and objects of this invention will be more fully described in connection with the accompanying drawing and 30 will be more particularly pointed out in and by the appended claims.

In the drawing:—

Fig. 1, is a plan view of the engine head looking down onto the usual skeleton gasket to which the structure of my invention is 35 shown attached.

Fig. 2, is a sectional view on line 2—2 of Figure 1.

Fig. 3, is a sectional view on line 3—3 of Figure 1.

40 Fig. 4, is an enlarged sectional view on line 4—4 of Fig. 5, showing how the strip is insulated from the gasket and the engine.

Fig. 5, is a plan view thereof.

Like characters of reference designate 45 similar parts throughout the different figures of the drawing.

As illustrated, 1 designates the block of the engine which is provided with intake valves 2 and exhaust valves 3. The head is 50 designated at 4 and the usual interposed gasket at 5. There is provided the usual combustion chambers 6 to which the valves 2 and 3 open, the said valves being at one side of the cylinder bores 7. I have shown 55 spark plugs 8, extending downwardly through the head 4, the terminals 9 thereof

being in relatively close superposed relation to the intake valves 2. It will be understood that this is merely a conventional showing of one type of engine merely sufficient to illustrate one application of the device of my invention thereto. 60

Next referring to one part of the means for vaporizing the mixture, and its other functions, 10 designates what may be a continuous metal strip, or a strip made up of sections, and which extends lengthwise of the engine and across the path of flow of the mixture passing from the intake valves 2, into the combustion chambers 6. This 65 strip 10, which I have shown to be continuous, extends across portions 11, of the skeleton gasket 5, and is preferably although not essentially, attached thereto, and in any event, it rests upon the gasket. There are 70 many advantages in actually attaching this strip to the gasket, and I consider this a novel feature of my invention so to do. As shown in Figs. 4 and 5, the gasket 5 is preferably grooved and in the bottom of the 75 groove a sheet of electrical insulation 12 slightly wider than strip 10. A like insulating sheet 13, is disposed on top of said strip. Fasteners 14, secure the strip and insulation to the gasket but do not pass 80 through strip 10, and hence the latter is electrically insulated from the engine and is 85 movable into and out of place together with the gasket 5, and can be sold in commerce with the latter. Abreast of the valves 2, I 90 preferably impart a turn to a short section of the strip, as indicated at 15, so that a flat face, instead of an edge, is presented toward the mixture flowing from the intake valve 2. 95

This strip is shown included in a circuit having a limb 16 connected with one end of the strip and connected with a source of current supply 17, which may be the battery of the car. The other limb of the circuit 100 is indicated at 18, the strip 10, forming a resistance. This may be arranged so that a switch may be employed to be closed before starting the car to heat the strip and thus heat the air and vapor in all the combustion chambers 7, with a view of vaporizing the mixture so that the engine may be readily started. After the first effective explosion or explosions, this circuit may be opened, and then the strip will be highly 105 heated by combustion in chambers 7, and this heated strip will not only serve to more 110

completely vaporize all the mixture, but will, in addition, vaporize any oil that may be pumped into the engine by defectively working pistons. Thus, by insuring vaporization of oil, carbon deposits on the valve seats will be prevented and hence the maximum compression retained.

I consider my invention complete and operative as thus far described, but I have found that great advantages flow from the additions of certain other features which I will next describe in detail.

In each chamber 7, and in superposed relation to the valves 2 and 3, I dispose strips 16, which are preferably arcuate, the ends 17 being disposed on and secured to the gasket 5, by means 18. These arcuate strips 16 are shown as having portions which not only lie close to the terminals 9, but which also are disposed in an elevated area with respect to the intake valves so that whatever incoming mixture that was not vaporized by the strips 10, would be acted upon by strips 16. I consider it a feature of this invention to dispose portions of the heating or vaporizing strips 16 in close proximity to, and specifically in surrounding relation with terminals 9, and in the specific form shown, I provide an opening 19, in each strip 16, and with this arrangement, I am able to subject the terminals to a most effective action of heat to prevent fouling of the terminals.

It will be understood that these strips 10 and 16 will be of very thin steel or any material of such a character that will be quickly heated to a high temperature. Thus, in those areas between the walls of the combustion chamber, and adjacent the valves, there will be highly heated elements for efficiently vaporizing not only the explosive mixture, but also any lubricating oil that may have been pumped into these chambers.

I consider it a feature of novelty to perforate portions 15, as indicated at 15' so that they will also act as breakers to break up the mixture.

It is believed that my invention will be clearly understood from the foregoing, and I do not wish to be limited thereto except for such limitations as the claims may import.

I claim:—

1. In combination, an explosion engine having a combustion chamber and intake and exhaust valves opening to said chamber, ignition terminals above the intake

valve, a primary metal vaporizing strip extending adjacent said valves for vaporizing the mixture and oil while the engine is running, means for heating said strip prior to the first explosion to vaporize the mixture, and a secondary metal strip extending abreast said valves and in close proximity to said terminals and adapted to be heated by combustion to prevent fouling of said terminals and also to assist in vaporizing the mixture.

2. In combination, an explosion engine having a combustion chamber and intake and exhaust valves opening thereto, said engine being divided into a block and head, a skeleton gasket interposed between said block and head, a flat strip of metal having its ends fastened to and electrically insulated from said gasket and engine and adapted to be heated by combustion after the first explosions to vaporize the mixture and oil, and means for electrically heating said strip prior to the first explosion to vaporize the mixture.

3. In combination, an explosion engine having a combustion chamber and intake and exhaust valves opening thereto, a flat strip of metal having its ends mounted on said gasket and extending across and along said valves, a portion of said strip abreast of the intake valve being turned up to present a flat face toward the mixture flowing from said valve, and said turned up portion being perforated to act as a breaker.

4. In combination, an explosion engine divided into a head and block and having a gasket therebetween, said engine having an explosion chamber and an intake valve opening thereto and ignition terminals in said chamber above said valve, and an arcuate vaporizing strip having its ends secured to said gasket and its intermediate portion extending upwardly abreast of and being slotted to permit projection thereinto of said terminals.

5. In combination, an explosion engine divided into a head and block and having a gasket therebetween, said engine having an explosion chamber and an intake valve opening thereto and ignition terminals in said chamber above said valve, and an arcuate vaporizing strip having its ends secured to said gasket and its intermediate portion extending upwardly along side of said terminals.

In testimony, that I claim the foregoing as my own, I hereby affix my signature.

EUGENE KRAFT.
